Primary Examiner — T. Chase Nelson*Assistant Examiner* — Jonathan J. Han(74) *Attorney, Agent, or Firm* — Barley Snyder(57) **CLAIM**

The ornamental design for a webbing fastener design, as shown and described.

DESCRIPTION

FIG. 1 is a front, top and right side perspective view of a webbing fastener;

FIG. 2 is a rear, bottom and right side perspective view of a webbing fastener;

FIG. 3 is a top plan view thereof;

FIG. 4 is a front elevation view thereof;

FIG. 5 is a rear elevation view thereof;

FIG. 6 is a bottom plan view thereof;

FIG. 7 is a left side elevation view thereof;

FIG. 8 is a right side elevation view thereof;

FIG. 9 is a rear, top and right side perspective view of the webbing fastener; and,

FIG. 10 is another front view of the webbing fastener.

Break lines are used in the drawings to indicate that any portions not shown between the paired break lines form no part of the claimed design.
